US0D1070674S

(12) **United States Design Patent** (10) **Patent No.:** **US D1,070,674 S**
(45) **Date of Patent:** **** Apr. 15, 2025**

(54) **RADIATOR GRILLE FOR VEHICLES**

(71) Applicants: **Hyundai Motor Company**, Seoul (KR); **Kia Corporation**, Seoul (KR)

(72) Inventors: **Seon-Min Kim**, Gyeonggi-do (KR); **In-Soo Hong**, Gyeonggi-do (KR)

(73) Assignees: **Hyundai Motor Company**, Seoul (KR); **Kia Corporation**, Seoul (KR)

(**) Term: **15 Years**

(21) Appl. No.: **29/888,855**

(22) Filed: **Apr. 5, 2023**

(30) **Foreign Application Priority Data**

Nov. 14, 2022 (KR) 30-2022-0046923

(51) **LOC (15) Cl.** **12-16**
